OIL AND GAS SEPARATOR

Edward J. Riley, Tulsa, Okla., assignor to Smith
Separator Corporation, Tulsa, Okla., a corpo-
ration of Oklahoma

Application September 26, 1933, Serial No. 691,064

8 Claims. (Cl. 183—2.7)

This invention relates to improvements in oil and gas separators and more particularly to stationary means for effecting a clean separation between oil and gas as they attempt to pass in admixture through the separator.

One of the objects of the invention is to provide improved unitary means which may be readily installed within the casing or tank of an oil and gas separator.

Another object is to furnish separating means comprising a number of parts which may be inexpensively manufactured and readily assembled to form a separating unit.

A still further object is to supply separating means including upper and lower concentric, slotted tubes, separated from one another by an imperforate umbrella shed which causes gas carrying entrained oil globules to travel in a circuitous path first through the lower tubes and subsequently through the upper tubes, so as to effectively knock out the oil globules from the gas stream.

A further object is to provide a separating unit of the above mentioned type having a crown disk at its top to compel passage of the gas stream outwardly into impact against the inner surface of the tank before the stream escapes from the latter, whereby any oil globules not separated by the slotted tubes will be caused to impinge against the inner surface of the tank and to thence flow downwardly into the lower portion of the tank.

With the foregoing objects outlined and with other objects in view which will appear as the description proceeds, the invention consists in the novel features hereinafter described in detail, illustrated in the accompanying drawings and more particularly pointed out in the appended claims.

In the drawings:

Fig. 1 is a side elevation partly in vertical section of a conventional type of oil and gas separator in which my invention is embodied.

Fig. 2 is an enlarged vertical sectional view partly in elevation of my improved separating unit.

Fig. 3 is a fragmentary horizontal sectional view taken on the line 3—3 of Fig. 2.

Referring to the drawings, 4 designates the tank of an oil and gas separator having an inlet pipe 5 terminating in a centrifugal or tangential nozzle 6 which has not been shown but may be of the type shown in U. S. Patent 1,779,023, dated October 21, 1930. A conventional float control 7 is arranged at one side of the tank and acts to control the outlet valve 8 through which oil is

discharged from the tank. Gas passes out of the tank by way of the outlet fitting 9. All of these parts are of known construction and they may be used with a heat exchanger 10 of the type shown in my U. S. patent application, Serial No. 682,719, filed July 28, 1933.

My present invention resides in a separating unit 11 of special type which is positioned in the tank between the inlet nozzle 6 and the outlet fitting 9. This unit comprises an umbrella shed 12 or frusto conical metal plate 12 of imperforate design, having its lower edge welded to the inner surface of the tank as shown at 13 to prevent any fluid from passing between said edge and the wall of the tank.

Lower concentric tubes 14, 15, 16, 17 have their upper edges secured to the plate 12 by any suitable means such as welding and the lower edges of these tubes are firmly secured to the upper surface of a funnel 18 which has a drop leg 19 for leading oil downwardly into the lower portion of the tank.

Each of the tubes is provided with vertical slots 20 and it will be noted that the slots of the tubes 14 and 16 do not extend to the tops of those tubes while the slots in the tubes 15 and 17 do not extend to the bottom. Consequently, the mixture of oil and gas, or wet gas in traveling through the slots from the exterior of the tube 17 to the interior of the tube 14 must travel in zigzag paths. The stream of wet gas at this stage is passed in chambers 17—16 and 15 and the velocity increased so that any fluid contained in the gas will be squeezed out and drained into funnel 18 where it will find passage into down pipe 19. Then when the gas enters the inner chamber 14 its velocity decreases by reason of the fact that chamber 14 is larger in capacity than chambers 15—16 and 17. The gas then comes into contact with the surface walls of chamber 14 and by scrubbing up against these walls any fluid in the gas will drop by force of gravity in chamber 14 and will likewise work its way into funnel 18 and thence into down pipe 19. It will be also observed that radially the slots of each tube are staggered relatively to the slots of the next tube to cause the gases in traveling to take a circuitous path.

Upper concentric, slotted tubes 21, 22, 23 and 24 have their lower edges secured to the upper surface of the umbrella shed 12 and the upper edges of these tubes are welded to a crown disk 25 which is of somewhat less diameter than the inner diameter of the tank. The slots 26 of the upper tubes are of about the same length as the height of the tubes in which they are arranged and the

slots of each of these tubes are staggered relatively to the slots in the next one of the upper tubes so that gas traveling from the inner tube 21 outwardly to the tube 24 will be caused to move in 5 a circuitous path.

The travel of the gas in passing from chamber 21 outwardly to 24 will act inversely from the procedure in lower chambers 15—16 and 17, in that the velocity of the gas moving outwardly in said 10 four chambers will be slowed down and any liquid that might be in the gas at that stage will drop on to the top of umbrella shed 12 and will find its passage into down pipes 29.

One or more holes 30 are provided in the lower 15 edge of the tube 15 so as to allow liquid deposited in the funnel 18 to flow downwardly into the pipe 19.

The tubes 14 and 21 may be integral with each 20 other, i. e. they may be made from a single piece 20 of tubular stock.

In operation, a mixture of oil and gas flowing from one or more wells is introduced into the tank 4 by way of pipe 5 and the nozzle 6 causes the mixture to move circumferentially about the 25 inner surface of the tank. The crude oil and heavier hydrocarbons will gravitate to the bottom of the tank and in so doing will pass through the tubes 31 in the heat exchanger 10 before discharging through the valve 8.

30 The gases containing the lighter hydrocarbons will rise above the oil level and some of these gases will rub against the inner surface of the tank on their way to the slots in the tube 17. These 35 gases at that particular stage are more or less saturated with crude oil, and the unit which I have designed and arranged in the separator is employed to extract to the maximum extent, the oil particles from the gas. The gas, upon rising in the separator, will come in contact with the 40 inner surface of the tank, and a portion of the oil droplets in the gas after being scrubbed against the walls of the separator will drop to the bottom of the latter by force of gravity.

Some of the gases will then come in contact 45 with the under surface of the umbrella shed and will be diverted through the slotted lower tubes 14 to 17, inclusive.

As the gases strike or impinge against the under surface of the umbrella shed they will be 50 compelled to flow through the slots of the lower tubes and in so doing will constantly impinge against solid surfaces of the tubes which face the slots, and in this way an additional amount of oil 55 particles will be knocked out of the gas and will gravitate into the funnel 18 and thence flow into the pipe 19. From the tube 14 the gases will rise into the inner one 21 of the upper tubes and will then travel outwardly successively through the 60 slots of the upper tubes, and of course, as the slots of the latter tubes are staggered, the gas will be forced to impinge against solid surfaces which will cause an additional amount of oil to be extracted 65 from the gas. This oil will flow down the upper surface of the umbrella shed and will be led by way of the parts 29 into the lower portion of the tank.

After leaving the slots of the tube 24, the gases 70 will be again compelled to flow outwardly beneath the crown disk 25 so as to finally strike against the inner surface of the wall of the tank for the purpose of extracting any additional amount of oil which may have remained commingled with the gas after leaving the slots of the tube 24. 75 Obviously any liquid gathering on the inner sur-

face of the tank wall above welding line 13, will gravitate into the pipes 29.

The gases flowing upwardly about the edge of the plate 25 will finally discharge through the fitting 9.

From the foregoing it is believed that the construction, operation and advantages of my improved separating unit may be readily understood by those skilled in the art and I am aware that changes may be made in the details disclosed 10 without departing from the spirit of the invention as expressed by the claims.

What I claim and desire to secure by Letters Patent is:

1. In an oil gas separator, a tank having a lower mixture inlet and an upper gas outlet, a partition plate positioned in the tank between the inlet and outlet, lower slotted concentric tubes positioned below said plate and having annular solid portions, said portions being staggered relatively to one another, a funnel arranged in the tank below the tubes and abutting against the lower edges of said tubes, upper concentric slotted tubes positioned above the partition plate, the slots of each of the upper tubes being staggered 25 radially relatively to the slots of each adjacent upper tube, means closing the upper ends of said upper tubes, all of said lower tubes being closed at their upper ends with the exception of the inner one of said tubes, said inner lower tube 30 communicating at its upper end with the inner one of said upper tubes, and pipes depending from the funnel and partition plate.

2. In an oil gas separator, a tank having a lower mixture inlet and an upper gas outlet, a partition plate positioned in the tank between the inlet and outlet, lower slotted concentric tubes positioned below said plate and having annular solid portions, said portions being staggered relatively to one another, a funnel arranged in the tank below 40 the tubes and abutting against the lower edges of said tubes, upper concentric slotted tubes positioned above the partition plate, the slots of each of the upper tubes being staggered radially relatively to the slots of each adjacent upper tube, 45 means closing the upper ends of said upper tubes, said lower tubes having their upper ends abutting against said partition plate, and the inner one of said lower tubes communicating at its upper end with the inner one of said upper tubes, and pipes 50 depending from the funnel and partition plate.

3. In an oil gas separator, a tank having a lower mixture inlet and an upper gas outlet, a partition plate positioned in the tank between the inlet and outlet, lower slotted concentric tubes positioned below said plate and having annular solid portions, said portions being staggered relatively to one another, a funnel arranged in the tank below the tubes and abutting against the lower edges of said tubes, upper concentric slotted tubes 60 positioned above the partition plate and having their lower edges abutting said plate, the slots of each of the upper tubes being staggered radially relatively to the slots of each adjacent upper tube, means closing the upper ends of said upper tubes, 65 all of said lower tubes being closed at their upper ends with the exception of the inner one of said tubes, said inner lower tube communicating at its upper end with the inner one of said upper tubes, and pipes 70 depending from the funnel and partition plate.

4. In an oil gas separator, a tank having a lower mixture inlet and an upper gas outlet, a partition plate positioned in the tank between the inlet and outlet, lower slotted concentric tubes positioned 75

- below said plate and having annular solid portions, said portions being staggered relatively to one another, a funnel arranged in the tank below the tubes and abutting against the lower edges 5 of said tubes, upper concentric slotted tubes positioned above the partition plate and having their lower edges abutting said plate, the slots of each of the upper tubes being staggered radially relatively to the slots of each adjacent upper tube, 10 means closing the upper ends of said upper tubes, said lower tubes having their upper ends abutting against said partition plate, and the inner one of said lower tubes communicating at its upper end with the inner one of said upper tubes, and 15 pipes depending from the funnel and partition plate.
5. In an oil gas separator, a tank having a lower mixture inlet and an upper gas outlet, a partition plate positioned in the tank between the inlet and 20 outlet, lower slotted concentric tubes positioned below said plate and having annular solid portions, said portions being staggered relatively to one another, a funnel arranged in the tank below the tubes and abutting against the lower edges of said tubes, upper concentric slotted tubes positioned above the partition plate, and having their lower edges abutting said 25 plate, the slots of each of the upper tubes being staggered radially relatively to the slots of each adjacent upper tube, a crown disk positioned above the upper tubes and abutting against the upper ends of the upper tubes, said lower tubes having their upper ends abutting against said 30 partition plate, and the inner one of said lower tubes communicating at its upper end with the inner one of said upper tubes, and pipes depending from the funnel and partition plate, said partition plate being imperforate with the exception 35 of a hole at its center to provide communication between the inner tubes of the lower and upper tubes, and being of frusto conical shape with its smaller end uppermost and its larger end secured to the inner surface of the wall of the tank by a gas-tight joint.
6. In an oil gas separator, a tank having a lower mixture inlet and an upper gas outlet, a partition plate positioned in the tank between the inlet and outlet, lower slotted concentric tubes positioned below said plate and having annular solid portions, said portions being staggered relatively to one another, a funnel arranged in the tank below the tubes and abutting 40 against the lower edges of said tubes, upper concentric slotted tubes positioned above the partition plate and having their lower edges abutting said plate, the slots of each of the upper tubes being staggered radially relatively to the slots of each adjacent upper tube, a crown disk positioned above the upper tubes and abutting against the upper ends of the upper tubes, said lower tubes having their upper ends abutting against 45 said partition plate, and the inner one of said 50
7. In an oil gas separator, a tank having a lower mixture inlet and an upper gas outlet, a partition plate positioned in the tank between the inlet and outlet, lower slotted concentric tubes positioned below said plate and having annular solid portions, said portions being staggered relatively to one another, a funnel arranged in the tank below the tubes and abutting against the lower edges of said tubes, upper concentric slotted tubes positioned above the partition plate and having their lower edges abutting said plate, the slots of each of the upper tubes being staggered radially relatively to the slots of each adjacent upper tube, a crown disk positioned above the upper tubes and abutting against the upper ends of the upper tubes, said lower tubes having their upper ends abutting against said partition plate, and the inner one of said lower tubes communicating at its upper end with the inner tube of the upper set, and drain pipes connected to the funnel and partition plate.

EDWARD J. RILEY.
